(57) **CLAIM**

I claim the ornamental design for a folding animal sustenance receptacle, as shown and described.

DESCRIPTION

FIG. 1 is an isometric view of a folding animal sustenance receptacle showing my new design in an open configuration.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an isometric view of the folding animal sustenance receptacle shown in a folded configuration;

FIG. 9 is a front elevation view thereof;

FIG. 10 is a top plan view thereof; and,

FIG. 11 is a right side elevation view thereof.

The illustrative broken line showing of bowls throughout the drawing figures depicts exemplary components which might be used with the foldable animal sustenance receptacle and forms no part of the claimed design.
